US0D1018536S

(12) **United States Design Patent** (10) **Patent No.:** **US D1,018,536 S**
(45) **Date of Patent:** **** Mar. 19, 2024**

(54) **CONTROLLER FOR AUGMENTED REALITY GLASSES**

(71) Applicant: **Beijing Xiaomi Mobile Software Co., Ltd.**, Beijing (CN)

(72) Inventor: **Shun Wang**, Beijing (CN)

(73) Assignee: **Beijing Xiaomi Mobile Software Co., Ltd.**, Beijing (CN)

(**) Term: **15 Years**

(21) Appl. No.: **29/738,066**

(22) Filed: **Jun. 15, 2020**

Related U.S. Application Data

(62) Division of application No. 35/507,124, filed on Dec. 14, 2018 (U.S. filing date under 35 U.S.C. 384), and having an international filing date of Dec. 14, 2018, now Pat. No. Des. 917,478.

(57) **CLAIM**

The ornamental design for a controller for augmented reality glasses, as shown and described.

DESCRIPTION

FIG. 1 is a front view of a controller for augmented reality glasses;

FIG. 2 is a rear view thereof;

FIG. 3 is a left view thereof;

FIG. 4 is a right view thereof;

FIG. 5 is a top view thereof;

FIG. 6 is a bottom view thereof; and,

FIG. 7 is a perspective view thereof.

1 Claim, 7 Drawing Sheets
